(57) **CLAIM**

The ornamental design for an adhesive tape, as shown and described.

DESCRIPTIONFIG. 1 is a front view thereof; and,
FIG. 2 is a rear view thereof.

The design shown in FIG. 1 consists of alternating text and pattern surfaces on the tape.

The broken lines depict environmental subject matter only and form no part of the claimed design.

The dot-chain lines illustrate a border of the claimed subject matter and form no part of the claimed design.

1 Claim, 1 Drawing Sheet**FIG. 1**

FIG. 2
